Primary Examiner — Kevin K. Rudzinski*Assistant Examiner* — Clare Ann Gannon(74) *Attorney, Agent, or Firm* — Scott T. Griggs; Griggs Bergen LLP(57) **CLAIM**

The ornamental design for a collapsible ground surface mat, as shown and described.

DESCRIPTION

FIG. 1 is a top perspective view of a collapsible ground surface mat, shown in a flat configuration;

FIG. 2 is a top perspective view thereof, shown in a folded configuration;

FIG. 3 is a top plan view thereof, shown in a flat configuration;

FIG. 4 is a left-side elevation view thereof, the right side view is a mirror image thereof;

FIG. 5 is a bottom plan view thereof; and,

FIG. 6 is a front elevation view thereof, the rear elevation view is a mirror image thereof.

The dashed lines in the figures depict environment that forms no part of the claimed design.

1 Claim, 3 Drawing Sheets(56)
